(57) **CLAIM**

The ornamental design for a vibrator battery control box, as shown and described.

DESCRIPTION

FIG. 1 is a view in side elevation from the front of the vibrator, showing my new design.

FIG. 2 is a view in side elevation from the back thereof, rotated 180° from that shown in FIG. 1.

FIG. 3 is a view in side elevation thereof, rotated 90° to the right from that shown in FIG. 1.

FIG. 4 is a view in side elevation thereof, rotated 90° to the left from that shown in FIG. 1.

FIG. 5 is a top plan view thereof; and,

FIG. 6 is a bottom plan view thereof.

The broken lines are for illustrative purpose only and form no part of the claimed design.
